UNITED STATES PATENT OFFICE.

DANIEL SAUDER, OF PETTISVILLE, OHIO.

WINDMILL.

SPECIFICATION forming part of Letters Patent No. 339,476, dated April 6, 1886.

Application filed September 16, 1885. Serial No. 177,256. (No model.)

To all whom it may concern:

Be it known that I, DANIEL SAUDER, a citizen of the United States, residing at Pettisville, in the county of Fulton and State of Ohio, have invented certain new and useful Improvements in Windmills; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a front view. Fig. 2 is a detail view showing crank-shaft. Fig. 3 is a side view. Fig. 4 is a section with parts broken away. Fig. 5 is a detail view with parts broken away. Fig. 6 is a sectional detail view of a portion of the operating mechanism.

This invention has relation to wind-engines; and it consists in the construction and novel combination of parts, as will be hereinafter fully described, and particularly pointed out in the claims.

Referring by letter to the accompanying drawings, A designates the derrick, and B is the platform near the upper end of the derrick, which is provided with an opening 30 through which an attendant may pass to repair or oil the upper portion of the engine when necessary. The derrick is of the ordinary construction, and is substantially braced to give it the necessary strength. The derrick is capped by a casting, C, which has a vertical axial bore, D, through which two vertical pitman-rods, E F, pass. Near its upper end the casting C is provided with an inwardly-extending arm, G, which has two vertical guide-slots, G' G', through which the upper ends of the vertical pitman-rods work. The upper end of one of the pitman-rods—viz, the rod E—is pivoted to the outer end of the upper arm, E', of a pivoted crank-lever, E", which is fulcrumed between the arms H H of the casting C below the connected upper ends of said arms. The upper end of the other pitman-rod, F, is connected to the upper end of an arm, J, the lower end of which arm J is connected with a wrist-pin, J', on the disk J" on the inner end of the wheel-shaft J". The

wheel-shaft J" works in a horizontal bearing, J', which extends forward from the turn-table or top casting. The vane M is hinged to the top casting and works in a horizontal plane. 55 The casting C has a rearwardly-extending horizontal bearing, L, in which is journaled a horizontal shaft, J", which is provided with an upwardly-extended arm, J", and a downwardly-extending rod, J', having an adjustable weight, J", secured thereto by a set-screw, J". This upwardly-extended arm J" is connected with the pivoted vane M by a link or rod, J", and the weight J" may be adjusted on its rod J' to require any desired force of wind to turn 65 the wheel into position for operation. The wind-wheel is preferably a slat-wheel having rigid slats, and the vane is a slat-vane. The lower ends of the pitman-rods E F are provided with pivoted or hinged metal arms N N', 70 which connect at their extreme lower ends with a double-crank shaft, O, mounted in bearings near the lower portion of the frame of the engine. The driving-shaft P is provided with a band-wheel, Q, on its outer end, 75 and a sectional clutch, R, and shifting-lever S, for throwing it in and out of gear. The pitman E is longer than the other pitman-rod, and passes through a guide, T, near the lower end of the frame. 80

U designates an eye on the weighted lever, with which eye a weighted cord is connected and runs over a pulley, V. This cord is used to turn the vane around parallel with the wheel when it is desired to throw the wheel 85 out of the wind. At its upper end one of the pitman-rods, E, is provided with a guide-casting, W', through which the casting V' on the upper end of the other pitman-rod works when the engine is in operation. 90

During operation the weight J" serves to keep the vane M in a position relatively at right angles to the plane of the wheel, as more fully shown in Fig. 1. When the wind strikes the face of the wheel, it causes the same to 95 rotate, turning the shaft J" and the disk J" on the inner end thereof. This causes the arm J to be driven up and down, and consequently the pitman F, connected thereto. This will cause the crank-lever E" to reciprocate vertically from its pivotal point, which is at the angle of its branches E' and H, and give a ver- 100

tical reciprocation to the pitman E, connected thereto. The horizontal arm being rigidly secured to the arm J, and the former pivotally connected with disk J² and the arm H of the crank-lever, it will be seen that when the pitman F is carried up the pitman E is carried down, thereby giving the said pitmen an alternate vertical reciprocation.

When it is desirable to throw the wheel 10 from the wind, it is only necessary to pull the cord leading from the arm J¹, which will cause the said arm to lift and the vane to turn in a position parallel to the plane of the wheel.

Having thus fully described my invention, 15 what I claim as new, and desire to secure by Letters Patent, is—

1. In a windmill, the combination, with the derrick and the casting journaled thereon and provided with the slotted guides for the pitmen, of the crank-levers respectively con-

nected with the pitmen, the wheel-shaft, the disk secured to the inner end thereof, and the crank-pin connecting one of the sector-shaped levers with the said disk, substantially as specified.

2. In a windmill, the combination, with a derrick and casting C, constructed as described, of the crank-lever E², having the arm E', the pitman connected with the said arm, the pitman F, wheel-shaft disk on the inner 30 end of the wheel, and the crank-lever having a hinge-joint and connected with the said disk, substantially as specified.

In testimony whereof I affix my signature in presence of two witnesses.

DANIEL SAUDER.
